E. A. CULBERTSON

PUMP

Filed Aug. 27, 1923

FIG. 1.

FIG. 2.

FIG. 3.

FIG. 4.

UNITED STATES PATENT OFFICE.

EDWARD A. CULBERTSON, OF WICHITA, KANSAS.

PUMP.

Application filed August 27, 1923. Serial No. 659,512.

To all whom it may concern:

Be it known that I, EDWARD A. CULBERTSON, a citizen of the United States, residing at Wichita, in the county of Sedgwick and State of Kansas, have invented a certain new and useful Improvement in Pumps, of which the following is a specification.

My invention relates to improvements in a certain type of pump previously invented by me, the fundamental principles of which are claimed in Letters Patent #1,433,677 issued to me October 31, 1922. But the improvements to be set forth in this specification are not exclusively limited to this type of pump, and may be applicable to pumps of other types.

One object of my invention is to provide suitable packing between the reciprocating plunger and the working barrel in a pump especially adapted to use in deep oil wells so as to prevent loss of efficiency due to leakage of the fluid past the plunger.

Another object of my invention is to devise a more effective type of plunger for a pump of the kind just mentioned.

A further object is to provide means of getting rid of sand or other foreign matter that might damage the plunger and its packing.

Still another object is to provide an improved release valve, designed to operate inside of a complete enclosure or housing, with seat set in a plug which is perforated and used for a screen.

An additional object is to provide below the standing or foot valve, and in conjunction therewith, a gas anchor or trap to prevent the entrance of gas into the working barrel of the pump.

The manner in which these various objects are attained will become clear during the following exposition of my invention which is illustrated by the accompanying drawings in which,

Figure 1 is a vertical, sectional elevation of the lower half of my improved pump, along the axis of the same.

Figure 2 is a similar sectional elevation of the upper half of the pump.

Figure 3 is a detail sectional view of the pump wall and working barrel at the upper set of packing rings.

Figure 4 is a detail exterior view of the lower end of the upper thimble of the working barrel together with the adjacent packing ring cups, with the sleeve which en-

closes them both in section, showing the weep grooves and holes for the elimination of sand.

In the drawings, which show the preferred form of my invention, 1 is a pump rod actuated from the surface of the ground by any suitable power system. This pump rod is fastened at 2 to a valve cage 3, having ports 4, and containing a ball valve 5 which is shown in closed position resting upon the valve seat 6. This valve seat is a separate member which is clamped between the valve cage 3 and the hollow plunger 7 at the point where the two are joined together by a threaded connection. The valve is so designed as to open on the downward stroke of the pump rod and plunger, and close on the upward stroke.

The plunger 7 reciprocates within a working barrel 8, which is made up of the sleeves 9, 10, and 11 which are threaded together at 12 and 13, as seen in Figure 2. It will be noted that the sleeve 10 is of greater diameter than sleeves 9 and 11, and that the latter sleeves are threaded inside of the former. Between the bottom of sleeve 9 and the top of sleeve 11, therefore, there is a considerable amount of annular space between the inner surface of sleeve 10 and the outer surface of the plunger 7.

In this space I insert packing rings 14, mounted in cups 15, as can be seen to best advantage in Figure 3. There are three sets of packing rings, three rings in each set, each ring mounted in its own separate cup or housing, as shown in Figure 2. The three sets of packing rings are separated from each other by the inner sleeves 16 and 17. These inner sleeves together with the packing rings and their cups fill up the annular space previously mentioned between plunger 7 and sleeve 10. And the entire ensemble of parts 9-17 constitutes the working barrel 8.

The arrangement just described is the one which I prefer, but it is capable of variation. For instance, the number of packing rings in each set may be either increased or diminished. There may be two sets of rings or there may be four, with one inner sleeve or three, as the case may be. Or the inner sleeves may be entirely dispensed with and the whole annular space between the plunger and the outer sleeve may be filled with the packing rings and their cups.

A further word of explanation may be

given here as to the operation of the packing rings, since this is one of the principal features of my invention. Packing rings are usually mounted in grooves upon the outer surface of a piston or plunger. They function by expanding so as to engage the smooth inner wall of the cylinder or barrel and thus prevent the escape of gas or fluid past the piston or plunger. The packing which is described and illustrated in this specification, however, operates in exactly the reverse manner. The rings 14, instead of being mounted upon the moving plunger, are mounted in the inner wall of the stationary working barrel. They function, not by expanding, but by contracting so that their inner surface engages the smooth outer surface of the plunger, thus preventing the escape of the fluid when the plunger is being raised. The circumference of the containing wall of the cups 15 is greater than the circumference of the outer wall of the rings 14 in order to give proper clearance to the rings when the pump is operating. The containing wall of the cups determines the limit beyond which the rings cannot be expanded, and may also serve to reinforce the rings.

In Figure 2 it will be noted that the lower end 18 of the plunger 7 is tapered so that it will readily enter the rings and spread them out when the plunger is inserted into the working barrel of the pump. After the plunger is inserted, however, it is of such a length, and the packing rings are so positioned in the working barrel, that during actual operation of the pump the lower end of the plunger is never raised above the rings, even at the highest point of the stroke; the rings are always in engagement with the plunger.

There are a number of advantages in the use of the new, improved packing just described. Where packing of the usual type is used it is with some difficulty that the piston or plunger is inserted into the cylinder or working barrel. And when the piston or plunger is removed the tendency of the rings is to spring open so that further difficulty is encountered when the piston or plunger is again inserted. All this difficulty I have eliminated. My packing rings act by contraction instead of expansion; and there is a fixed limit beyond which this contraction cannot go, i. e., at the point where the open ends of the ring engage each other. However great the pressure, the ring cannot contract beyond this point without buckling; whereas there is no limit to the expansion of a ring of the expandible type. It is easy therefore so to construct the new ring that, at its extreme point of contraction, it still fits snugly in its cup and its diameter is great enough to permit the ready insertion of the tapered end 18 of the plun-

ger. Thus it is apparent that the plunger can be entirely removed from the pump, if occasion demand, and replaced at will without the slightest difficulty, and without in any way lowering the efficiency of the packing.

A further advantage is seen in the ease with which the pump may be assembled. Sleeves 9 and 10 having been threaded together and then placed in an inverted position, three packing rings may be dropped each into an enclosing cup, and the cups then dropped into position within the sleeve 10. Inner sleeve 16 may then be dropped into position, followed by three more rings and cups, then inner sleeve 17 and the last set of rings and cups in like manner. Sleeve 11 is then screwed into the end of sleeve 10 and the working barrel is complete, ready for the insertion of the plunger. To any one who is familiar with the difficulties attending the assembling of a pump or motor with the old type of packing, the simplicity of this process will be apparent.

The principal advantage of the improved packing, however, lies not in its ease of assembling, but in the greater efficiency with which it functions in the actual operation of the pump. A pump used in deep oil wells needs to have heavy duty packing which can stand a great deal of rough usage and the wear and tear of abrasive foreign matter, such as sand, which gets into the working parts. My invention meets this need.

In Figures 2, 3, and 4 may be seen the weep holes 19 for the elimination of sand or other foreign material which may get in between the plunger and the working barrel. This feature of my invention is best understood by studying Figure 4 which shows the lower end of sleeve 9 in elevation, and the upper part of sleeve 10 in section. The cups 15 are also shown in elevation in their position immediately below sleeve 9. Here it is seen that there are apertures 20 in sleeve 9 discharging into an annular groove 21 which in turn discharges into apertures 19 in sleeve 10. On the down stroke of the plunger there is a steady flow of the fluid outwardly through these apertures which will flush out any sand or grit which might otherwise get into the packing rings.

All the parts thus far described are enclosed within an outer casing, which consists of well tubing 22 and the pipe 23. The latter is of greater diameter than the former since it must be roomy enough to house the working barrel and also provide an annular chamber 24 outside the working barrel for the upward passage of the fluid, as will be explained presently. The pipe 23 is swaged down at its upper end 25 and threaded on the inside where it is fastened to the well tubing 22 which extends upward to the surface of the ground, to carry the pumped fluid.

In order that the plunger and working barrel may be held rigidly in their proper position inside the outer casing, an annular casting 26 is fastened at the top of the working barrel and engages the inner surface of the pipe 23. This casting is provided with suitable vertical apertures so as not to interfere with the upward flow of the fluid.

Sleeve 11, which comprises the lower part 10 of the working barrel, is fastened at its lower extremity by the threaded connection 27 to the longitudinal passage casting 28, which in turn is fastened to pipe 23 at 29. Casting 28 is also fastened at 30 to pipe 31, 15 which is of the same diameter as pipe 23.

Longitudinal passage casting 28 is provided with two longitudinal passages, 32 which leads up into the working barrel 8, and 33 which leads up into the annular chamber 24 surrounding the working barrel. Passage 32 is always open at both ends so that fluid may flow through it in either direction. Passage 33, however, is controlled by a secondary valve 34 which comprises a housing 35 which is fastened at 36 to the longitudinal passage casting 28, and a ball valve 37. At the bottom of the ball cage or housing 35 is fastened a perforated casting 38 which acts as a strainer, and between them is clamped in position the valve seat 39. The movement of the ball is controlled by the inwardly projecting walls 40. The ball cage is completely enclosed. Instead of the open ports usually provided for 35 the escape of fluid from the ball cage (see 4 in Figure 2) there are deep grooves 41 between the inwardly projecting walls 40 through which fluid makes its way up into the longitudinal passage 33.

At the lower end of the pipe 31 is fastened the foot casting 42. The foot casting supports the foot valve 43 which is substantially the same as the plunger valve 3 already described. To the lower end of the 45 foot casting is fastened the pipe 44 which extends down into the fluid. Within the foot casting the gas anchor 45 is fastened at 46. Between the gas anchor and the pipe 44 is an annular chamber 47 which acts as 50 a gas trap. The gas anchor extends down

below the bottom of the pipe 44, so that in pumping the fluid is drawn from below the accumulation of gas.

The operation of the pump is substantially the same as that of the pump originally invented by me and described in Letters Patent #1,433,677. On the upward stroke of the plunger, foot valve 43 opens and the fluid pours into pipe 31, moves upward through port 48 into longitudinal passage 32 and thence into the working barrel 8. On the downward stroke, the foot valve closes, and plunger valve 3 opens simultaneously, the fluid filling the hollow plunger and rushing through the valve into the well tubing 22. Ordinarily, the down stroke of the plunger would be slow on account of the resistance of the fluid, and effort to hasten it would be liable to cause the rod 1 to buckle. But this disadvantage is obviated 70 in my invention. As soon as the downward stroke begins, secondary valve 37 opens simultaneously with the plunger valve. The pressure of the plunger upon the imprisoned fluid forces it up through the secondary valve 75 into longitudinal passage 33, thence through port 49 into the annular chamber 24 through which it passes upward into the well tubing 22. Thus it will be seen that in my invention the fluid is pumped upward 80 on the down stroke of the plunger as well as on the up stroke.

What I claim as new, and desire to secure by Letters Patent is:—

The combination in a pump of a hollow plunger, a sectional plunger barrel composed of a series of connected sleeves, a plurality of series of packing rings disposed between the plunger and one of the barrel sleeves, an inner sleeve or spacer interposed between each series of packing rings, one of the barrel sleeves provided with an outwardly opening annular groove and having a series of radial openings leading from said groove to the outer surface of the plunger 90 barrel, and a series of radial openings in the barrel sleeve adjacent to the sleeve carrying the annular groove and in combination therewith.

EDWARD A. CULBERTSON.
